ASH TRAY

Harold F. Bartley, Worcester, N. Y.

Application August 2, 1949, Serial No. 4,245

Term of patent 14 years

(Cl. D85—2)

To all whom it may concern:

Be it known that I, Harold F. Bartley, a citizen of the United States, residing at Worcester, in the county of Otsego and State of New York, have invented a new, original, and ornamental Design for an Ash Tray, of which the following is a specification, reference being had to the accompanying drawing, forming part thereof.

Fig. 1 is a perspective view of an ash tray embodying my new design;

Fig. 2 is a top plan view of the same; and
Fig. 3 is a side elevation thereof.

I claim:

The ornamental design for an ash tray, substantially as shown.

HAROLD F. BARTLEY.
